J. Franklin Meyers
ATTORNEY

UNITED STATES PATENT OFFICE.

ARTHUR A. MORSE, OF BALTIMORE, MARYLAND, ASSIGNOR TO THE TIN DECORATING COMPANY OF BALTIMORE, OF BALTIMORE, MARYLAND, A CORPORATION OF NEW JERSEY.

CONTAINER AND SPOUT STRUCTURE.

Application filed July 14, 1925. Serial No. 43,512.

My invention relates to containers of a type which require a spout for conveniently pouring the contents, and to spout structures to co-operate therewith.

5 The invention consists in novel features of construction or arrangement of the container to co-operate with a detachable spout, in a spout structure or arrangement adapted to co-operate with the container and also having novel features irrespective of such adaptation, and in the combination of the container and the spout.

The container top is provided with a nipple having screw threads or equivalent means 15 for the ready connection and disconnection of a spout in convenient position for pouring, and also with a recess in which the cap portion of the spout may be located and detachably secured with substantial firmness 20 for shipment. The container bottom has a special formation or concavity so that when two or more containers are superposed for packing and shipment the concavity of any superposed container accommodates an upwardly projecting part of the spout located 25 in the recess of the lower container. This prevents injury to the spout, and also enables superposed containers to be packed in a space no greater than is required by the dimensions 30 of the containers themselves, without allowance for projecting portions, such as the spouts located in idle position in the container top recesses.

In addition to its construction or arrangement for co-operation with the container nipple and recess, the spout structure includes a new and improved swivel arrangement by which the spout proper may be turned at any angle to the base or screw cap 35 portion, to facilitate the positioning of the spout for convenient pouring.

I will now describe one representative embodiment of the invention in physical form, and after considering this example, skilled 45 persons will understand that many variations may be made within the principles of the invention; and I contemplate the employment of any structures that are properly within the scope of the appended claims.

50 Fig. 1 is a perspective view of a container or "can" and spout, embodying the invention in one form.

Fig. 2 is a side elevation of the upper por-

tion of one can and a superposed can with certain parts in section. 55

Fig. 3 is an enlarged sectional detail showing the can top recess and spout construction.

Fig. 4 is a side elevation of the spout looking at the nozzle end. 60

The container is not limited, in the broader aspect of the invention, as to form or material, but the invention is especially valuable in connection with sheet metal containers, usually called cans, in which liquids are 65 placed for shipment and use, and it will therefore be sufficient to explain the invention as embodied in sheet metal structures of the can type.

In a preferred form the can side wall or 70 walls 1 and 2 have a top 3 and a bottom 4 secured to them in standard fashion, namely, by crimp formations 5 and 6. The form of the top and bottom and the method of attachment are such that the top and bottom 75 edges 7 and 8 respectively, project substantially above the top 3 and bottom 4 respectively, or in other words, the main flat portions of the top and bottom are substantially inset or recessed with relation to the 80 top and bottom edges.

The top 3 is provided with an upward projecting nipple 10, which may be formed integrally with the top or may be a separate piece attached thereto. The nipple is formed 85 for the convenient connection and disconnection of the cap portion of a spout structure, this formation being represented by screw threads 11. Any similar or equivalent arrangement, such as bayonet joint formations, 90 or interrupted threads, may be substituted. The nipple top 12 is continuous or imperforate, and is preferably provided with a central depression 13 to facilitate the location of the point of a puncturing tool for making a 95 central perforation when it is desired to pour the can contents. The nipple 10 is usually located near one side wall, or preferably, as shown in Fig. 1, near a corner of the can, when the latter is of polygonal shape. Usually 100 the nipple projects somewhat above the level of the edge 7; this projection is taken care of by the recess at the bottom of any superposed can, as shown in Fig. 2.

A recess or socket 15 is formed in the top 105 3 and usually this is located substantially

centrally. The recess has a tapering or approximately conical wall 16 and its bottom 17 is usually perforated as at 18 for filling, and this perforation is then sealed 5 by solder 19.

Figs. 3 and 4 show a co-operating spout structure including a base or cap portion 20 and a spout portion 21. The cap is formed with screw threads to co-operate with the 10 threads of nipple 10 and its bottom portion is formed with a flare or flange 22, the periphery of which is dimensioned to fit snugly against the tapered socket wall 16 near the bottom thereof, or in other words, the cap 15 flange has a substantially tight friction fit against the side wall of the socket, sufficient to retain it in position for shipment, but permitting ready removal for use. The spout proper, 21, may in some cases be 20 rigidly secured to the cap or base portion 20; but to permit the spout to be easily turned to convenient pouring position after the cap has been screwed upon the nipple 10, without necessity for any care in the formation 25 of the screw threads or other attachment devices to insure that the spout will point in the proper direction when the cap is screwed down tight, it is preferred to provide a swivel connection of the spout upon 30 the cap. For this purpose the spout includes a bottom portion 25 formed with an aperture in which the central portion of the cap top surrounding an aperture formed therein, is pressed or spun, forming a lip 35 26 overlying the spout bottom around its aperture. This connection may be made before the top member 30 is applied. The top member has a concave elongated formation. Its main edges lie upon the upper 40 surface of the bottom piece 25 and are secured by a continuous upturned and pressed flange 31. Toward the nozzle this flange has ears 32 which are bent up and pressed upon the nose portion of the top 45 piece 30, completing the nozzle formation, as easily understood from Fig. 4 without further explanation. In this or equivalent ways the spout proper 21 may be rotated to any convenient position, usually substantially as indicated in Fig. 1, after the cap 20 is screwed down tight on the nipple. In brief, the spout is usually directed outward and diagonally, so that it has a substantial 50 overhang for the convenient pouring of the liquid contents of the can into any other receptacle. After pouring the spout may be turned back so that it lies over the can top and there is then no danger of injury to the 55 spout by contact with objects alongside the can.

When the cans are filled and ready for shipment, a spout is applied to each can in inactive position by inserting the cap 20 in the can top socket 16 and pressing it down

so that the periphery of the flange 22 frictionally jams against the side wall of the socket, and the spout is thus retained with sufficient security against accidental displacement, but may be easily removed for use, merely by pulling it up. 65

The spout structure may in some cases be so dimensioned that it will not project sufficiently to engage the ordinary flat bottom of a superposed can; but in order to make the spout of convenient size and 70 shape, at least one portion, such as the highest portion 35 of the top member 30, projects high enough to strike the bottom of a superposed can, if the bottom is flat, as usual. Therefore each bottom 4 is preferably 75 formed with an upward curvature or concave portion 40, which is usually substantially central to conform with the central location of the socket 16. This concavity accommodates any projecting part of the 80 spout, such as the highest part 35, in a manner which is obvious in Fig. 2, and permits any number of cans to be superposed and to occupy the smallest possible space in shipment without danger of injury to the spouts 85 by contact with superposed can bottoms, and with the additional advantage that all the spouts, except those located on the top can in the stack, are thoroughly protected 90 against injury or the possibility of displacement and loss. 95

While the pivotal or swivel connection of the spout proper to its base 20 is very desirable, in a detachable spout structure of this type, it is not necessarily limited to a detachable spout, or one designed to co-operate with a temporary holding socket, such as 16. 100

I claim:—

1. A container having a nipple adapted to detachably receive a spout structure for pouring and having also means for detachably holding the spout structure in idle position for shipment, the bottom of the container having a concavity to accommodate a projecting portion of a spout located in idle shipping position at the top of an underlying container. 105

2. A can structure comprising a recessed top having a screw-threaded nipple located near one side of the can and adapted to detachably receive a spout structure for pouring and also having a substantially centrally-located socket having tapered side walls, a spout structure adapted to co-operate with the nipple and socket, and including a cap threaded to detachably engage the nipple, and having a flange adapted to frictionally fit the socket side walls. 115

Signed at Baltimore State of Maryland this 9th day of July A. D. 1925. 120

ARTHUR A. MORSE.
